APPARATUS FOR CHASING RINGS

Bertram W. Sager, Highland Park, and Mason M. Sager, Chicago, Ill., assignors to Paramount Wedding Ring Co. Inc., Chicago, Ill., a corporation of Illinois

Application March 19, 1956, Serial No. 572,240

9 Claims. (Cl. 41—1)

This invention relates in general to the method of and apparatus for indexing, chasing, and otherwise ornamenting circular articles such as finger rings, and is more particularly designated as an automatic apparatus pneumatically operated for accomplishing the desired results.

Heretofore it has been the practice in decorating rings to do the work entirely by hand. This not only is tedious and monotonous, but it is very difficult to match up different ring decorations and to have the decorations appear uniform throughout the entire surface. Such manual labor is also expensive because it takes the time of a highly paid artisan to do the work.

The present invention is designed and intended to provide automatic means for controlling the ornamenting stroke or indentation, the feeding of successive objects to be decorated, and the number of operations for each ring.

An important object of the invention is to provide an apparatus which operates automatically to carry out the method of decorating rings and similar articles in accordance with this method.

A further object of the invention is to provide a pneumatic controlled apparatus for carrying out the feeding, turning and hammering operations in properly timed succession.

A further object of the invention is to provide means for separately controlling the hammer pressure, the ring advance and the forward and rearward movement of a support which moves a ring under the hammer.

A further object of the invention is to provide timing means for varying the application of pressure to the hammer, ring advance and mandrel moving operations.

Still a further object of the invention is to provide means for varying the number of operations of the hammer for different ring sizes.

Still a further object of the invention is to provide a multiple armed hammer in which the different arms may be provided with different implements for producing different chasing effects upon a ring blank at different locations thereon or at the same location for varying the decorative results on the ring blank in accordance with the timed movement of the different hammers.

Other objects of the invention will appear in the specification and will be more apparent from the accompanying drawing in which,

Fig. 1 is a perspective view of an apparatus for carrying out the method of chasing rings in accordance with this invention.

Fig. 2 is a perspective view of a portion of the apparatus shown in Fig. 1 substituting a multiple armed hammer support for the single armed support as shown in Fig. 1.

Fig. 3 is a perspective view of a portion of the apparatus shown in Fig. 1 relating to the ring feeding, mandrel engaging and hammer operations.

Fig. 4 is a block diagram of the operating parts and their connections as shown in Fig. 1.

Fig. 5 is a diagrammatic view of a multi-arm hammer device in accordance with Fig. 2 which may be used in

place of the single armed hammer construction as shown in Fig. 1; and

Fig. 6 illustrates a ring blank with a number of different chasings which may be applied thereto in regular succession to complete a ring.

It is desirable to supplement the artistic manual operations upon rings and similar articles with an accurate mechanical treatment of the ring surfaces so that an artisan will not be devoting his entire time to the application of purely mechanical chasing which may be done by automatic apparatus of the present type. The increasing cost of labor also promotes the addition of automatic apparatus for performing those purely mechanical chasing operations which can be done more accurately and quickly by pneumatic apparatus of this kind.

Referring now more particularly to the drawings, a number of ring blanks A to be indented, ornamented or chased are mounted upon a rod 12 which is rotated upon a pivot 14 between projections 16 supported by a base plate 18. The outer end of the rod 12 when turned downwardly about its pivot is moved just short of the path of the two upper and lower slide parts 20 and 22 which have notches 24 and 26 respectively for engaging the ring blank from the end of the rod 12 which terminates just short of the path of the slides, and the end ring is pressed from the end of the rod against a fixed plate 21 at the opposite side of the slide bars 20 and 22 by means of a spring 23 on the rod 12 extending between the mounting projections 16 and the rings mounted on the rod tending to press them from the outer end of the rod. The inner adjacent ends 28 and 30 of these slide parts are beveled so that they will embrace and slide over the outermost ring more easily to lodge it in the notches 24 and 26. A pneumatic piston and cylinder device 32 engages 35 the rear ends of the upper and lower slide parts 20 and 22 and advances the ring for the next operation.

In order to hold a ring yieldingly between the slide parts 20 and 22, a coil spring 34 is secured to the upper end of a pin 36 which extends freely through the upper slide part 20 and is secured to the lower slide part 22 with the lower end of the spring bearing on the top of the upper slide part and the upper end secured to the upper end of the pin 36, thereby tending to press the slide parts yieldingly together.

In front of the ring gripping slide parts is a bearing 38 through which a tapered mandrel 40 is moved back and forth by a pneumatic piston and cylinder device 42.

To pick up a ring advanced by the slide parts 20 and 21, the mandrel 40 is moved so that its outer end is out of the path of the slide parts and as the mandrel is then advanced through the bearing 38, it will pick up a ring blank carried by the slide parts 20 and 22, and will move the ring blank until it is tightly engaged upon the mandrel. The mandrel is moved by its pneumatic device 42 until the ring blank is close to an anvil head 44 for supporting the mandrel and below a hammer 46 carried by a hammer head 47 and advanced by a pneumatic piston and cylinder device 43 and retracted by a spring 49. The cylinder device is retracted upwardly by a spring 48.

The cylinder device is supported in an upright position by a clamping arm 50 attached to an upright fixed support 52 attached to the supporting base plate 18, and the hammer head 47 is supported by an arm 51 also secured to the fixed support 52 and below the cylinder device 43.

In the anvil head 44 is a split supporting collar 55, the parts of which are pressed against the mandrel 40 so that the split parts are spread as the mandrel is pressed through the anvil head which forms a limiting support for positioning a ring blank A under the hammer 46 as shown more clearly in Fig. 3. At the outer

side of the anvil head is a guideway 57 which may be attached to the base plate 18 and forms a slide for a movable block 59, through which the outer end of the mandrel 40 is adapted to pass. This block is pressed toward the mandrel by a spring 61 connected at its outer end to a rod 63 which extends loosely through the block 59 and is attached to the anvil head 44 with the inner end of the spring bearing against the outer face of the block 59 and tending to move the block on its guideway until a perforation in the block through which mandrel extends tightly engages the end of the mandrel. Thus the mandrel is inserted through the anvil head 44 and into the block 59 until it makes a firm connection therewith and then the block 59 is moved back with the anvil on its guideways against the spring 61. This always insures that the outer end of the mandrel is firmly supported no matter what size of ring is carried by the mandrel.

In the bearing 38 is another split collar 55 closely engaging the mandrel and adapted to engage a finished ring blank as it is carried rearwardly by the mandrel 40 and disengaging the ring blank therefrom as the mandrel is withdrawn.

A blow is imparted to a ring blank A on the mandrel 40 by the hammer 46. The hammer is retracted by its spring 49 and the pneumatic device 43 is retracted by its spring 48. The mandrel is turned a portion of a rotation by a motor 43 to bring the next portion of the ring into position to be engaged by the hammer. The number of operations of the hammer upon any ring is controlled by any one of the indexing rings 54, 56, 58 or 60 which may be connected for operation with the mandrel depending upon the size of the ring and the number of tool engagements desired on the surface thereof.

When the mandrel is rotated a complete turn, it is stopped by the operation of a timing device 62 and is withdrawn by its pneumatic device 42 from engagement with the anvil head, and as the mandrel passes through its bearing 38, the ring carried thereby will either engage a wiper 64 between the anvil head 44 and the bearing 38 or it will engage the split collar 55 which disengages the ring from the mandrel and drops it into a tray or other receiver (not shown).

The method of operation is thus briefly described; a ring blank or a plurality of such blanks to be chased are mounted upon the feeding rod 12 which has a spring for discharging ring blanks into the path of a slide having upper and lower slide parts 20 and 22 for engaging a ring and moving it at right angles to the holding rod 12 into the path of the mandrel 40. The mandrel picks up each ring blank and carries it into a fixed position below a hammer which is operated automatically to engage the outer surface of the ring blank with a tool; the mandrel is supported for any ring position and in different locations for rings of different sizes and is rotated step by step to bring the entire surface of the ring into engagement. After the ring has been completely decorated, the tool operations are stopped and the mandrel is withdrawn with the ring discharging the completed ring as it is withdrawn, positioning the mandrel for repeating this operation.

Suitable parts are provided for carrying out the various operations by electrical and pneumatic means and in connection with a timer, the relative location of the parts being shown in Fig. 1, and the connection and operation of the parts being further shown in the block diagram of Fig. 4.

In the block diagrams of Figs. 4 and 5, additional designating characters are included for convenience and clearness: M indicating motors, MS micro-switches, S, Solenoids, R relays and CL a clutch.

The mandrel 40, its operating motor 41 and the timing or indexing rings 54, 56, 58 and 60 are preferably mounted upon a plate 70 slidable in guideways 72 mounted on

the base plate 18 and moved back and forth by a piston rod 74 extending from the cylinder device 42, the outer end of the piston being secured to a projection 76 at the end of the plate 70 so that the cylinder device 42 receives pressure at one end and is pressed by a spring in the other direction, the piston rod and the plate 70 are moved accordingly.

At the rear end of the plate 70 is a micro-switch M-1 which is engaged and operated by the plate at the rear 10 end of its travel. Near this end of the plate is a projection 78 for operating a micro-switch M-2, in the forward direction only of movement of the plate; and near the other end of the guideway 72 is a micro-switch M-3 operated by a projection 80 on the plate 70 after 15 a ring is picked up by the mandrel 40.

A micro-switch M-4 is mounted on the bearing 38 in the path of a movable head 82 of the piston and cylinder device 72 so that the arm of the switch is engaged when the ring slide parts 20 and 22 have moved a ring in a 20 position to be picked up by the mandrel 40.

For each pneumatic piston and cylinder device there 25 is an electric controlling valve which may be manually set with an indicating gage therefor which are represented as receiving fluid under pressure from a supply press main 84.

Each of the pneumatic piston and cylinder devices 30 32, 42 and 43 is represented as having a spring return for one direction of movement of the piston therein, either within the cylinder or externally thereof. There 35 are also fluid pressure pipes 86, 88 and 90 for connecting each of the respective piston cylinder devices through manually adjustable valves 92, 94 and 96, each of which has a gage 98, 100 or 102 for indicating the pressure admitted through that pipe connection. In addition, a 40 manual control valve 104 connected to a pressure supply pipe 106, controls the fluid pressure admitted to the piston and cylinder device 42 which is indicated by a gage 108.

The piston cylinder device 42 for operating the mandrel 40 and its slide plate 70 has a back pressure or exhaust relief pipe 110 which together with the pressure supply pipe 88 are connected through a common valve 112 controlled by an electric valve 114 which causes the valve to admit pressure through the supply pipe 88 and exhaust from the cylinder 42 through the pipe 110.

A separate pipe 116 connects the fluid pressure from the valve 104 to one end of the electric valve 114.

An electric valve 118 controls the supply of fluid pressure through the pipe 88 to the ring advancing cylinder device 32, which is returned by spring pressure when the fluid pressure is cut off.

Valves 92 and 96 are connected to the pressure supply pipe by a connector pipe 120 and connecting the valve 96 with the supply pipe 90 for the hammer, piston and cylinder device 42, are two electric valves 122 and 124, the latter connected by a bypass 126 to insure an adequate supply of fluid under pressure through the pipe 90 connected between these valves. An exhaust pressure line 128 is also connected to the pipe 90 which is controlled by an electric valve 130 for insuring relief of pressure upon the hammer piston and cylinder device 43 in timed relation to the pressure strokes thereof.

The timing device 62 comprises a motor 132 which rotates a shaft 134 carrying cams 136, 138 and 140, the first of which actuates a contact arm 142 to a homing and holding relay 144 for the motor 132. The next cam 138 operates a contact arm 146 for a relay 148 for controlling the drop hammer movement; and the contact arm 150 is operated by the cam 140 for controlling a relay 152 relating to the indexing operation.

The motor 132 is connected to a suitable source of current supply by a switch 154 and conductors 155 and the relays 144, 148 and 152 may also receive a suitable source of current at the same time. This motor 132 oper-

ates continuously as long as the apparatus is in operation and the cams and relays control the timed operation of the parts to which they relate.

The mandrel rotating motor 41 has conductors 156 extending to a switch 158 for connecting it with a suitable source of supply with a looped portion 160 of the wires connecting them to permit a sliding movement of the plate 70. This motor has a shaft 162 for connecting it to the mandrel upon which indexing rings 54, 56, 58 and 60 are adjustably mounted and the shaft 162 is connected to the motor through a clutch 164 which allows the motor 41 to run continuously and to stop at any one of the positions indicated by pins 166 projecting from the indexing rings.

Each indexing ring has a solenoid 168 for projecting an arm 170 into the path of the pins 166 of its ring, the number of pins on the ring determining the number of stops of the mandrel and consequently the number of points that may be engaged by the hammer.

Each solenoid for the successive rings is actuated by one of the switches P, Q, R or S so that the closing of a selected switch will project the arm 170 into the path of its pins. One of the indexing rings has a long pin 172 which projects into the path of a micro-switch M-5 suitably secured in position to engage the long pin and operative to stop the rotation of the mandrel 40 when a certain movement or a rotation is completed. This micro-switch 5 is connected by a conductor 174 to relay 148 which relates to the drop hammer cam 138 and by a conductor 176 to the micro-switch M-4 which relates to the operation of the ring advance cylinder 32 and thence by conductor 178 to the electric valve 114 which controls the supply pressure through valve 112 to cylinder device 42.

Another conductor 180 extends from the switch 114 back to the drop hammer relay 148. The drop hammer relay is also connected by a conductor 182 with micro-switch M-3 and thence through conductors 184, 186 and 180 to the drop hammer electric valves 122, 124 and 130.

The solenoids for the switches P, Q, R and S are connected by conductors 188 with relay 152 for controlling the operation of the solenoids by the operation of the cam 148. In operation, the switches for the motors 132 and 41 may be turned on as both of these motors are intended to run continuously as long as the apparatus is in operation. The other connections are made through the relays in a well known manner, and in general, the timer contacts are closed when the contact arms are engaged in the notches of the cams. The cam 136 of the timer is a homer cam which is driven by the motor 132 to the same relative terminal position before starting each new cycle of operation.

Assuming that the plate 70 is in its rearmost position, and the ring holder rod with ring blanks thereon is rotated downwardly to bring the outermost ring into the path of the slide parts 20 and 22, the starting operation with the motors running causes a circuit to be established from relay 144 through micro-switches M-1, M-2 and electric valve 118 by means of conductors 190 and 192. The valve 92 which admits fluid under pressure to pipe 86 for operating a cylinder device 32 which then picks up a ring blank and advances it into the path of the ring mandrel 40.

This movement of the ring feeding cylinder device 32 closes the micro-switch M-5 which completes a circuit properly timed to electric valve 114 through conductors 174, 176 and 180 back to relay 148 which admits fluid under pressure through pipe 88 to the mandrel moving device 42. This causes a forward movement of the slide plate 70 carrying mandrel 40 and as the micro-switch M-2 is engaged, the circuit is broken to the electric valve 118 which allows the ring feeding device 32 to be withdrawn by its inner spring to pick up another ring blank. At this time, however, the outer end of the mandrel is engaged in and picks up the ring blank and advances it to the anvil position under the hammer.

The engagement of micro-switch M-3 by the projection 80 causes a circuit to be established from relay 148 through conductors 182, 184, 186 and 180 to the electric valves 122 and 124 which admit fluid under pressure 5 through the pipe 90 to the hammer operating pressure device 43.

The hammer is operated in quickly repeated strokes a number of times depending upon the number of pins 166 upon the particular indexing ring which has been chosen 10 for the ring blank and the hammering operation is continued throughout the whole periphery of the ring due to the operation of the cams 138 and 140 in connection with their relays and the switch circuit of the particular indexing ring which has been chosen. The mandrel is rotated 15 a portion of a complete circle by the motor 41 and the clutch 164 depending upon which engagement arm 170 is advanced into the path of the pins 166 of the indexing ring. The operation of the cam 140 will send an impulse into one of the solenoids 168 which will withdraw the arm 20 170 to pass one of the pins but to engage the next one and the operating hammer device 43 will be given an impulse by its electric valves 122 and 124 for each stroke. The quick return of the device 43 by its return spring is insured by the electric exhaust valve 130 which is timed 25 for such operation.

When the entire surface of a ring has been covered, the long pin 172 engages the micro-switch M-5 which opens the circuit from the relay 148 through electric valve 114 for the mandrel operating device 42 returning the 30 mounting slide plate 70 by the return spring of this device and activating all relays with the slide in engagement with micro-relay M-1 for repeating the operation.

To change the number of ring chasings upon any blank, it is necessary only to open the closed switch P and to 35 close one of the other switches as R. The location of the micro-switch M-3 may be varied on one of the guide rails 72 by means of an attached clamping device 194 which may include a thumb screw or any other conveniently operated attaching means.

40 As above described, a ring blank will be similarly decorated or chased throughout the entire surface, but additional decorations may be placed thereon by reengaging the partly decorated ring blanks and also a multiple armed chasing device is represented in Fig. 5 45 in which a number of tool holders 200 are mounted on separate arms 201 extending from a common hub 202 which may be rotatable upon a fixed support 52 as shown in Fig. 1. This hub has a ratchet wheel 203 secured thereto with a reciprocating pawl 204 for engaging it, 50 the pawl being moved in one direction by a piston and cylinder device 205 and return by an internal spring thereof. The device 205 receives fluid under pressure from a pipe 206, controlled by an electric valve 207 for receiving fluid under pressure from a supply pipe 120 55 as shown in Fig. 4.

One object of this construction is to provide a ring blank A as shown in Fig. 6 with a number of different decorations as D1, D2, D3, D4, D5 and D6 around the periphery thereof, either in regular succession or mixed 60 or interposed or mingled with each other. To accomplish this result, the ring feeding and mandrel operating parts may be the same as shown in Fig. 4, but the indexing rings may be somewhat different. A separate indexing ring R-1, R-2, R-3, R-4, R-5 and R-6 may be provided for each of the separate tools carried by each of the arms. These indexing rings each have a number of short pins 208 and a long pin 209. Each indexing ring has a separate solenoid 210 for advancing its arm 211 in contact position to engage the short pins 208 65 and a micro-switch 212 having an operating arm which extends into the path of its long pin 209.

With this construction, the different tools carried by the holders 200 may be brought automatically into operation by cams, relays and operating circuits similar to 70 the cams 138 and 140, the relays 148 and 152 and con-

ductor connections 174, 188 and 176 heretofore referred to.

In operation, the ring will be advanced by the mandrel 40 as previously explained to the anvil operating position and instead of the continuous operation of a single tool, the multiple armed tool holder will be rotated successively, bringing the different tools in operation in accordance with the settings of the indexing rings as previously described.

A sample operation both for a single tool and for multiple tools is thus described in detail, and since the construction and operation of the pneumatic devices, the control valves, both manual and electrical, the indicators therefor, the timing switches, and the solenoids, as well as many of the other individual parts are well known in construction and operation, it is unnecessary to describe them in detail.

The multiple armed tool holder makes it possible to vary the decoration of a ring, and by changing the tools or changing the succession in which they are operated, a great many new designs and combinations may be automatically applied to ring blanks by this method of operation. Successive rings may be differently decorated by simply halting the operation after one ring is complete and changing the positions of the indexing rings to produce different tool operations or results in different successions.

In the form shown in Fig. 5, one piston and cylinder 43 will be used for hitting all of the different tools carried by the tool heads 200. Although six different tool heads are shown, a greater or less number of such heads may be used.

It is also noted that different pressures may be applied to the piston and cylinder devices and that these pressures as applied may be changed by manual operation of the valves relating thereto. Although a combination of electric and air operated devices are shown and described, it is obvious that the operating parts may be all air or all electric and an electric hammer may also be used. Air valves may be substituted for the micro-switches and for the other electric valve devices.

While an apparatus both single and multiple armed for carrying out this method of ring chasing has been described in some detail, it should be regarded by way of illustration and example rather than as a restriction or limitation thereof, as many changes in the construction, combination and arrangement of the parts may be made without departing from the spirit and scope of the invention.

We claim:

1. In an apparatus for chasing rings, the combination with a rod for mounting rings to be chased, of a slide movable transversely to the end of the rod for picking rings in succession from the end of the rod and moving them therefrom, a graduated mandrel movable into the path of the individual rings and disengaging the rings therefrom, a hammer movable to engage ring blanks on the mandrel, means for rotating the mandrel for successive strokes of the hammer, and means withdrawing

the mandrel from the hammer and discharging the chased rings.

2. A ring chasing apparatus in accordance with claim 1, in which the ring feeding rod is mounted to rotate about a pivot at the time thereof and a coil spring is mounted on the rod adjacent the pivot tending to press the rings from the other end thereof.

3. In an apparatus according to claim 1, a plate at the end of the ring blank holding rod for engaging the outermost ring, and the plate spaced from the end of the rod, and a slide member with spring pressed slide parts for engaging opposite sides of the outermost ring and moving into the path of the mandrel.

4. In an apparatus in accordance with claim 3, a pneumatic operating device for the sliding parts, and timing means for controlling the movement of the slide into and out of the path of the mandrel.

5. In an apparatus in accordance with claim 1, the mandrel having a bearing through which it is movable to pick up one of the ring blanks, and the bearing having a wiper for engaging the ring blank when it is chased and discharging it from the mandrel as it is withdrawn through the bearing.

6. In a ring chasing apparatus in accordance with claim 5, a pneumatic operating device for positively advancing and withdrawing the mandrel from the chasing position, and timing means for partly rotating the mandrel a predetermined number of times for each complete rotation.

7. In a ring chasing apparatus in accordance with claim 1, the reciprocating hammer having a pneumatic operating device, and means for varying the force of each blow directed by the hammer.

8. In a ring chasing apparatus in accordance with claim 1, a tool holder having a plurality of arms movable under the hammer to impart different designs to a ring blank as the position of the arms is changed to vary the decoration applied to a ring.

9. In a ring chasing apparatus in accordance with claim 8, a rotatable multiple armed tool holder movable under the hammer and means for rotating the tool holder to bring different tools into operation for successive strokes of the hammer.
